UNITED STATES PATENT OFFICE.

JOSEPH HOTCHNER, OF SAN FRANCISCO, CALIFORNIA.

ILLUMINATED SIGN.

1,295,826.

Specification of Letters Patent. Patented Feb. 25, 1919.

Application filed April 22, 1918. Serial No. 229,894.

To all whom it may concern:

Be it known that I, JOSEPH HOTCHNER, citizen of the United States, residing at San Francisco, in the county of San Francisco, State of California, have invented a new and useful Illuminated Sign, of which the following is a specification in such full and clear terms as will enable those skilled in the art to construct and use the same.

10 This invention relates to an electric sign of the type in which the body of the sign is thicker than the edges of the sign for the purpose of providing a sufficient space within which to install the electric wiring, 15 while improving the edge appearance of the sign on account of the narrowness of the frame supporting the letters.

It will be understood by those skilled in the art that with this type of electric sign, 20 it is necessary to provide a border of some kind to improve the appearance of the sign, and with this sign the borders are carried in standard stock lengths and may be used either for signs in which the letters are arranged horizontally or on signs in which the letters are arranged vertically thereby dispensing with the necessity for carrying a separate stock of letters for these two purposes.

30 Another object of the invention is to provide a sign body which will have flush letter surfaces throughout its length and height except at its sides or top of the sign, thereby eliminating the accumulation of dirt and 35 dust.

Other objects of the invention will appear as the description proceeds.

An embodiment of the invention is shown in the drawings in which the same reference numeral is applied to the same portion throughout, but I am aware that there may be modifications thereof.

Figure 1 is a front elevation of a portion of a sign built according to the invention 45 disclosed herein,

Fig. 2 is a transverse vertical sectional view of a sign built in accordance with the invention disclosed herein,

Fig. 3 is a side elevation of a vertical 50 sign built in accordance with this invention,

Fig. 4 is a front elevation of one of the letters detached from the sign body,

Fig. 5 is an edge view of the letter shown in Fig. 4 showing the crimped edges of the 55 letter which overlap or underlap the next adjacent letter or border,

Fig. 6 is an edge elevation of the letter shown in Fig. 4 looking at right angles to Fig. 5,

Fig. 7 is a front elevation of one of the 60 border plates,

Fig. 8 is an end elevation of one of the border plates,

Fig. 9 is a plan view on a slightly larger 65 scale of one type of border corner,

Fig. 10 is a section of the border corner taken on the line 10—10 of Fig. 9,

Fig. 11 is a plan view of one form of mitered border corner,

Fig. 12 is a plan view of the mitered 70 border corner which is adapted to fit the corner shown in Fig. 11, and

Fig. 13 is an edge elevation of the border corner shown in Fig. 11 showing the overlap at its mitered edge.

75 Fig. 14 is a plan view of a portion of the border plates of a sign in which a slightly different form of mitered corner is used from that shown in the preceding figures, and

Fig. 15 is a plan view of the connecting plate used on the mitered corner shown in Fig. 14.

The numeral 1 indicates the top rail of the sign, 2 the bottom rail thereof, which 85 rails are formed of suitable channel steel connected together to form a support for the several letters. The letters each comprise plates 3 with raised portions 4 and 5 adapted to overlap the next adjacent plate top or 90 bottom, as the case may be. Each of the plates is provided with such a number of sockets 6, each carrying a lamp L, as may be desired.

95 It will be observed that the letter plates are substantially plane sheets of metal which may be painted or enameled as desired.

In order to space the letters of opposite sides of a sign away from one another, plates 100 7, 8 and 9 are connected with the channels 1 and 2 respectively, and they each have two flat portions 10 and 11 which connect respectively with the channel iron frame of the sign, and with the letter plates. Suitable screws or bolts are used to connect the plates 8, 9 and 10 with the channel plates

105 and with the letters, so that the letters stand away from one another double the distance between the two plates of the flat portions 110 10 and 11 of the plates 7 plus the width of the channel iron used. The plates 7 abut

against angle corners 13 which are the same for all corners of a sign, whether vertical or horizontal, and they have a figure 15 on the border thereof which matches the figures 5 16 on the border of the plates.

Arrangements are made so far as possible to have the holes 16 in the border plates 7 and in the mitered plates 13 at standard distances from one another, so that in the 10 assembly of the sign the minimum labor will be required.

If desired, the border plates shown in Figs. 11 to 13 may be used in which the border plates 17 and 18 form one complete 15 corner, the plate 17 having a raised portion 19 cut on a miter to overlap the mitered edge of the plate 18. When the sign is assembled, it will be observed that the border is the same whether used vertically or horizontally, 20 and in each case the surface of the plate carrying the letter is raised from the frame of the sign body up a distance equivalent to the distance between the two parallel planes of the border plates. The front of the sign 25 is therefore all in substantially one plane, and the same letters and border may be used equally well for the production of a vertical sign or a horizontal sign.

In Fig. 14, the border plates are similar 30 to those used in the preceding figures except that the flanges 30, 31, 32 and 33 are cut square so that they will lie in the same plane, and the beveled portion of the plate 34, 35 is cut to fit as well as it conveniently 35 will, after which it is covered with an overlapping beveled plate 37, which is provided with holes to connect to the two plates 34, 35, and which makes a perfect finish for the border over the joined corners of the inclined portion of the plates 34, 35.

Having thus described my invention what I claim as new and desire to secure by Letters Patent of the United States, is as follows, express reservation being made of 45 permissible modifications.

1. An illuminated sign comprising a frame, a series of flat letter plates, a series of border plates having two parallel edge portions one of which carries a decoration,

the edge portions being connected with a 50 portion inclined to both edge portions, means to connect the letters and border, means to illuminate the letters and corner plates for joining the end and side border plates to complete the finish of the sign. 55

2. An illuminated sign comprising a frame, a series of border plates having portions parallel to each other in two different planes and connected by a plate inclined to both of the parallel portions, a corner finishing plate adapted to overlie the beveled portion of the border plates at the joining corners, a series of letters connected with the border plates, and means to illuminate the letters. 60 65

3. A sign comprising a frame, a series of letter plates, a series of border plates each having two parallel portions in different planes and an intermediate portion inclined to and connecting the parallel portions, 70 means to connect the border plates, frame and letter plates to produce a beveled edge sign, and corner plates having portions in two planes to complete the finish of the sign. 75

4. A sign comprising a frame, a series of letter plates, a series of border plates for the ends and sides of the sign; each border plate having two parallel portions in different planes and an intermediate portion inclined to and connecting the parallel portions, and means to connect the border plates, frame and letter plates to produce a beveled edge sign. 80

5. A sign comprising a frame, a series of letter plates, a series of border plates for the sides and ends of the sign each having two parallel portions in different planes and an intermediate portion inclined to and connecting the parallel portions, the end border plates being substantially the same as the 90 side border plates, means to connect the border plates and letter plates to the frame to produce a beveled edge sign, and corner plates for completing the finish of the sign. 95 85

In testimony whereof I have hereunto set 95 my hand this 12th day of April, A. D. 1918.

JOSEPH HOTCHNER.
